TOOTH BRUSH AND POWDER CONTAINER

Robert E. Ley, Dover, Ohio

Application January 11, 1936, Serial No. 58,721

11 Claims. (Cl. 132—84)

It is desirable, especially in traveling, to carry one's tooth brush in a sanitary container. Tooth powder or other dentifrice is usually carried in a separate container, and it is always inconvenient to keep two containers ready at hand and manipulate both of them every time one's teeth are brushed.

This invention relates to a combined tooth brush and tooth powder container, and more particularly to a container in which some of the powder therein may be applied to the brush before it is removed from the container.

Certain prior containers which are adapted to house both the tooth brush and the tooth powder, have required first removing the brush and then shaking powder onto the brush from a powder compartment of the container.

Other prior containers have required removing a separate powder capsule from the main container and shaking powder from the capsule onto the brush. These operations are awkward and troublesome and inevitably result in spilling some of the powder.

Accordingly, it is an object of the present invention to provide an improved combined tooth brush and powder container, in which a small amount of the powder may be deposited on the brush bristles with the container entirely closed.

Another object is to provide a combined tooth brush and powder container from which the brush may be easily removed ready for use.

A further object is to provide a combined tooth brush and tooth powder container having a relatively large powder compartment which may be easily replenished at any time.

Another object is to provide a combined tooth brush and powder container in which the brush bristles may be moistened and powder from the container applied thereto before the container is opened.

A further object is to provide a combined tooth brush and powder container which has no loose parts to be detached from the container when the powder is applied to the brush and the brush removed for use.

A still further object is to provide an improved tooth brush and powder container which is easy and convenient to use, and which is attractive, compact, lightweight, and inexpensive to manufacture.

These and other objects are accomplished by the improvements comprising the present invention which may be stated in general terms as including a container having a brush compartment and a powder compartment and means for

providing communication between the compartments when the container is closed.

In the drawing forming part hereof:

Figure 1 is an elevation of one form of my invention in a partially open position;

Fig. 2 is an end view thereof;

Fig. 3 is a longitudinal sectional view thereof in closed position;

Fig. 4 is a transverse sectional view as on line 4—4, Fig. 3;

Fig. 5 is a partial elevation as on line 5—5, Fig. 4;

Fig. 6 is an elevation of a modified form of my invention;

Fig. 7 is an end view thereof; and

Fig. 8 is a detached view partly in section of the powder compartment casing used in the modified form of Fig. 6.

Similar numerals refer to similar parts throughout the several views of the drawing.

The improved container shown in Figs. 1 to 5 inclusive includes walls forming a casing indicated generally at 9 constituting a tooth powder compartment 10, and a cover indicated generally at 11 hingedly connected to the casing 9 at one side of the powder compartment. The cover 11 is preferably substantially U-shaped in cross section and adapted to form with the casing 9 a brush compartment 12 at one side of and coextensive with the powder compartment 10 when the cover is closed, the brush compartment being adapted to contain a tooth brush and handle of any standard size.

Preferably a longitudinal partition wall 13 divides the container into two compartments and constitutes the side of the powder compartment adjacent to the brush compartment.

The partition wall 13 is preferably formed with a gradual reverse curve at 14 to form a reduced portion 15 at one end of the powder compartment.

A closure member 16 is adapted to slidably fit in the other end of the powder compartment and provides a means of replenishing the powder therein. Preferably the closure member 16 is provided at its upper side with an angular portion 17 terminating in the longitudinally extending flange 18 which acts to hold the handle end of the brush in position against the partition wall 13 when the container is closed.

Ears 19 are provided on the angular portion 17, and the cover 11 is hinged to the ears 19 by means of a pin 20 passing through the ears and the side walls of the cover.

Thus the cover 11, flange 18 and closure 16

are all connected together and may be disconnected as a unit from the powder compartment casing at any time by pushing against the flange 18 to slide the closure 16 out of the powder compartment.

Preferably, a side wall 22 is provided on the powder compartment casing 9 at one side thereof and forms one side of the brush compartment. The side wall 23 at the other side of the brush compartment is preferably cut away at the reduced end 15 as shown at 24, and the cover 11 is provided with an extension wall 25 which fits into the cut away portion 24 when the cover is closed.

15 Preferably the side wall 22 and the extension wall 25 are each provided with a series of apertures 26 for admitting air or moisture to the brush compartment.

As shown in Fig. 1 when the cover 11 is opened, 20 one side of the bristle end of the brush is exposed to facilitate its removal from the container.

At the reduced end portion 15 of the powder compartment, the partition wall 13 is provided with an elongated aperture 28 for providing communication between the powder compartment and the brush compartment adjacent the bristles 29 of a brush 30 therein. Movable means normally closing the opening 28 may include a slide or sleeve member 31 slidably mounted around 25 the reduced end 15 of the powder compartment casing. The slide 31 is adapted to be moved longitudinally thereon to open or close the opening 28, as indicated in dot-dash lines in Fig. 1, and may be provided with a pin 32 extending 30 through the opening 28 into the powder compartment for the purpose of loosening the powder and preventing it from caking at the opening 28.

The slide 31 is preferably provided at its lower 40 side with a protuberance 33 for being engaged by the thumb or finger, and the slide extends through a slot 34 in the side wall 22 and between the extension wall 25 and partition wall 13 at the other side of the container, so that the slide 31 may easily be moved longitudinally to the extent that the pin 32 can move in opening 28, by pushing upon the protuberance 33 at the outside of the container.

In using the improved container, assuming 50 that the powder compartment is filled and the brush positioned in the brush compartment in closed position as shown in Fig. 3, the container is first inverted or turned upside down and the slide 31 is then moved toward the adjacent end 55 of the container to uncover opening 28, by pressing upon the protuberance 33 of the slide.

By tapping the powder compartment lightly at the reduced end thereof a small amount of tooth powder will be deposited on the bristles 29 of the brush. If it is desired to moisten the bristles before the powder is applied, the same may be 60 easily accomplished by holding the apertures 26 under a water faucet or the like prior to opening the slide 31.

65 After the powder has been deposited on the brush the slide 31 is moved to close the opening 28 and the cover may then be swung to open position, whereupon the brush is easily removed ready for brushing the teeth.

70 The gradual curve shown at 14 in the partition wall 13 provides for feeding the powder into the reduced end of the powder compartment without any substantial caking thereof, and the slide 31 provides means operable externally of the con-

tainer for depositing a small amount of powder on the bristles of the brush with the container closed so as to avoid any spilling of the powder.

The form of container shown in Figs. 6, 7, and 8 is generally similar to that shown in Figs. 1 to 5 inclusive, and is adapted to be used where it is desired to provide a capsule or powder refill container which may be sold already packed by the manufacturer. By means of this detachable refill powder casing, the old powder casing may be 10 discarded when emptied, and replaced by a new one already packed by the manufacturer.

The form of improved container shown in Figs. 6, 7, and 8 preferably includes a powder capsule or casing indicated generally at 109 and 15 having the same general shape as the powder compartment casing shown in Figs. 1 to 5. The casing 109 has the curved partition wall 113 at one side thereof forming the reduced end portion 115, and the partition wall 113 at the reduced 20 end is provided with an opening 128 which is adapted to be closed by a movable slide 135. At its other end the casing 109 may be provided with a temporary closure 136 when it is filled 25 with powder by the manufacturer.

The cover 111 is hinged to a closure cap member 137 by pins 120, and the closure member 137 fits slidably over the end of the casing 109 and also provides an end closure for the handle end 30 of the brush 130.

Preferably, the straight part of the partition wall 113 along the large portion of the capsule, is dished or concave as indicated at 113', and the closure cap 137 has a concave partition wall 137' fitting over and conforming to the concave wall 35 113'.

In this form of my invention, the cover 111 is provided with extended side walls 138 at each side of the bristle end of the brush compartment, for slightly overlapping the reduced end portion 40 115 of the powder compartment when the container is closed.

The extended side walls 138 are preferably each provided with a series of perforations 126 for admitting moisture or air to the brush compartment.

In Figs. 6, 7, and 8, the slide 135 is shown slidably mounted on the reduced end portion 115 by means of ribs or tracks 140 on opposite sides of said portion 115, and the slide has side flanges 50 141 which are bent outward, around and under said ribs. Thus the slide may be operated with the finger at the side of the powder compartment instead of at the bottom, and the ribs 140 engaging the flanges 141 hold the slide closely against 55 the powder opening 128.

Obviously, either type of slide 31 or 135 may be used on either form of my invention.

In using the latter form of my invention, when the powder compartment casing 109 has been 60 emptied, the same may be slid out of the closure 137 and discarded, and a new casing 109 filled with powder as shown in Fig. 8 may be inserted into the closure 137.

Both embodiments of my invention provide a 65 combined container for both tooth brush and tooth powder, in which a small amount of the powder may be deposited upon the brush before opening the container, thus avoiding the spilling of powder, and making the operation of preparing the tooth brush for use an extremely simple one.

The improved container has no loose parts to be detached and is attractive, compact, light in weight, and easily used.

I claim:

1. A combined tooth brush and powder container including walls forming a brush compartment adapted for detachably containing a standard tooth brush having a handle, and a tooth powder compartment coextensive therewith, a wall of the brush compartment being hinged to the container to provide a cover for said brush compartment, a longitudinal partition wall between the compartments having an opening adjacent one end of the brush compartment, and movable means normally closing said opening.
2. A combined tooth brush and powder container including a casing forming a powder compartment, a cover substantially U-shaped in cross section and movably associated with said powder compartment to form a brush compartment at one side thereof for detachably containing a standard tooth brush having a handle, the powder compartment casing being coextensive with said brush compartment and having an opening adjacent one end of the brush compartment, and movable means operable externally of the container normally closing said opening.
3. In combination with a standard tooth brush having a handle, a tooth brush and powder container including walls forming a casing, a longitudinal partition wall dividing said casing into a brush compartment and a powder compartment, said tooth brush being detachably contained in said brush compartment and said powder compartment being coextensive therewith, a longitudinal wall of the brush compartment being movable away from the powder compartment to open the brush compartment, the partition wall having an opening therein communicating with one end of the brush compartment, and movable means operable externally of the container for closing said opening.
4. A tooth brush and powder container substantially equal in length to a standard tooth brush having a handle and including a longitudinal partition wall dividing the container throughout its length into a brush compartment and a powder compartment, said partition wall having an opening communicating with one end of said brush compartment, an outside wall of the brush compartment at said end having apertures therein, and movable means operable externally of the container for closing the opening in said partition wall.
5. A tooth brush and powder container including a casing forming a powder compartment, a removable closure for one end of said compartment, a U-shaped cover hinged to said closure and forming a brush and handle compartment at one side of and coextensive with said powder compartment, said powder compartment casing having an opening adjacent one end of said brush compartment, and movable means operable outside of said casing for closing said opening.
6. A tooth brush and powder container includ-

ing a casing forming a powder compartment, one longitudinal wall of said casing being curved to form a reduced portion at one end of the compartment, a removable closure for the other end of said compartment, a U-shaped cover hinged to said closure and forming a brush and handle compartment at the curved wall side of and coextensive with said powder compartment, and said curved wall having an opening at said reduced end portion communicating with said brush compartment.

7. A tooth brush and powder container including a casing forming a powder compartment, one wall of said casing being curved to form a reduced portion at one end of the compartment, a removable closure for the other end of said compartment, a U-shaped cover hinged to said closure and forming a brush and handle compartment at one side of and coextensive with said powder compartment, said powder compartment casing having an opening in its reduced end portion communicating with said brush compartment, and a sleeve member slidably mounted around said reduced end portion for closing said opening.

8. A combined tooth brush and powder container including a casing forming a powder compartment, a cover substantially U-shaped in cross section and movably associated with said powder compartment to form a brush compartment at and coextensive with one side thereof, the powder compartment casing having an opening adjacent one end of the brush compartment, a slide movably mounted on said casing for closing said opening, and a pin on the slide extending into said powder compartment.

9. In combination with a tooth powder capsule having one side shaped to conform to the handle and bristles of a tooth brush, a removable closure for one end of said capsule, and a cover hinged to said closure for enclosing a tooth brush positioned along said shaped side of said capsule.

10. In combination with a tooth powder capsule having one side shaped to conform to the handle and bristles of a tooth brush, a removable closure for one end of said capsule, a cover hinged to said closure for enclosing a tooth brush carried alongside of said capsule, the capsule having an opening therein at the end adjacent the brush bristles, and a slide movably mounted on said capsule for closing said opening.

11. A combined tooth brush and powder container including a powder compartment casing, having one side conforming to the handle and bristles of a tooth brush, a cover movably associated with said powder compartment casing to form a brush compartment, a removable closure cap for the end of said casing adjacent the brush handle, the other end of said casing having an opening adjacent the brush bristles, and a slide on the casing accessible outside the cover for closing said opening.

ROBERT E. LEY.
